(57) **CLAIM**

The ornamental design for the handle system for a container, as shown and described.

DESCRIPTION

This application is related to the commonly assigned design patent application Ser. No. 29/673,304 by Gerber et al. filed on Dec. 13, 2018, and entitled “Malleable Handles for a Container”, the entire subject matter of which is incorporated herein by reference.

FIG. 1 is a front view of the handle system for a container shown with an exemplary container;

FIG. 2 is a back view of the handle system for a container of FIG. 1;

FIG. 3 is right side view of the handle system for a container of FIG. 1;

FIG. 4 is a left side view of the handle system for a container of FIG. 1;

FIG. 5 is a top view of the handle system for a container of FIG. 1;

FIG. 6 is a bottom view of the handle system for a container of FIG. 1;

FIG. 7 is a front view of the handle system for a container of FIG. 1 shown without the container;

FIG. 8 is a back view of the handle system for a container of FIG. 1 shown without the container;

FIG. 9 is right side view of the handle system for a container of FIG. 1 shown without the container;

FIG. 10 is a left side view of the handle system for a container of FIG. 1 shown without the container;

FIG. 11 is a top view of the handle system for a container of FIG. 1 shown without the container; and,

(Continued)

FIG. 12 is a bottom view of the handle system for a container of FIG. 1 shown without the container.

The broken lines in FIGS. 1-6 illustrate unclaimed environment and unclaimed portions of the handle system for a container which form no part of the claimed design, and the broken lines in FIGS. 7-12 illustrate unclaimed portions of the handle system for a container which form no part of the claimed design.
